UNITED STATES PATENT OFFICE.

JOHN N. BATTISTA, OF NEW YORK, N. Y.

SHOE.

1,286,499.

Specification of Letters Patent.

Patented Dec. 3, 1918.

Application filed March 7, 1918. Serial No. 221,036.

To all whom it may concern:

Be it known that I, JOHN N. BATTISTA, a subject of the King of Italy, residing at New York, county and State of New York, have 5 invented new and useful Improvements in Shoes, of which the following is a specification.

This invention relates to an improvement in shoes, and the object is to provide a novel 10 construction in the top or upper of a shoe, and particularly adaptable to shoes having high tops or uppers.

A further object resides in the method or 15 manner of fastening the top portion of the shoe so that a neat appearance is presented and causing the upper to fit snugly about the leg of the wearer.

The invention consists of certain novel 20 features of construction and combinations 20 of parts which will be hereinafter described and pointed out in the claims.

In the accompanying drawing:—

Figure 1 is a view in side elevation of a 25 shoe showing the invention;

Fig. 2 is a detail perspective view showing the shoe open at the top; and

Fig. 3 is a detail sectional view disclosing 30 the manner of fastening the top or upper portion of the shoe.

In the drawing, the shoe is designated A, and the inner section of the upper as 1, and 35 the outer section of the upper as 2. The forward or front edges of the upper sections are fastened together by suitable stitching.

The outer section of the upper is formed 40 in two parts, an upper and lower portion 3 and 4, respectively. The lower portion is shown as divided throughout its length and 45 provided with suitable eyelets 5 for the reception of a lacing 6 for drawing the two sections of the upper together around the instep and ankle of the foot.

The inner section 1 of the upper and the 50 lower portion 4 of the outer section are stitched together at the back of the shoe, and covering the seam formed is a strip 7.

The strip 7 extends the full length of the upper and is stitched to the uppermost portion of the inner section 1. Attached to the 50 inner face of the back strip 7 in a suitable manner, is a vertical row of studs 8.

The upper portion 3 of the outer section of the upper, is of sufficient length to overlap the upper edge of the lower portion 4 55 to a sufficient degree to provide a closure and present a neat appearance. Fastened to the outer face and along the rear edge of the upper portion 3 is a row of sockets 9, which are adapted to receive the studs 8 for fastening 60 the upper portion 3 of the upper to the back strip.

When the back strip 7 is fastened to the upper portion 3 an appearance is presented 65 indicating that the upper portion is rigidly secured thereto, as the fastening means is entirely concealed. By this method of fastening the upper or top portion of the shoe will be drawn tightly around the leg or limb of the wearer and a smooth and snug fit produced.

What I claim as my invention and desire to secure by Letters Patent, is:—

1. A shoe comprising an upper, consisting of inner and outer sections, the outer 75 section having upper and lower portions, the lower portion being connected at its rear edge of the inner section, and detachable means for fastening the rear edge of the upper portion of the outer section to the 80 rear edge of the inner section.

2. A shoe comprising an upper consisting of two sections connected together along their front edges, one of the sections having upper and lower portions, the lower portion being 85 connected at its rear edge to the rear edge of the full section, a back strip extending the length of the upper and connected to the full section and the lower portion of the other section, and detachable means for 90 fastening the rear edge of the upper portion of the section to the back strip.

JOHN N. BATTISTA.
